UNITED STATES PATENT OFFICE.

ISRAEL K. DIXON, OF JOHNSTOWN, PENNSYLVANIA, ASSIGNOR TO THE LORAIN STEEL COMPANY, A CORPORATION OF PENNSYLVANIA.

TONGUE-SWITCH.

No. 826,409.

Specification of Letters Patent.

Patented July 17, 1906.

Application filed July 26, 1905. Serial No. 271,290.

To all whom it may concern:

Be it known that I, ISRAEL K. DIXON, of Johnstown, in the county of Cambria and State of Pennsylvania, have invented a new and useful Improvement in Tongue-Switches, of which the following is a full, clear, and exact description, reference being had to the accompanying drawings, which form a part of this specification.

10 My invention has relation to certain new and useful improvements in tongue-switches, and designed to provide a **T**-rail tongue-switch of simple, novel, and durable construction.

15 With this object in view my invention consists in the novel construction, arrangement, and combination of parts, all substantially as hereinafter described, and pointed out in the appended claims, reference being had to the accompanying drawings, in which—

Figure 1 is a plan view of a tongue-switch embodying my invention; and Figs. 2, 3, and 4, transverse sections taken on the lines 2 2, 3 3, and 4 4, respectively, of Fig. 1.

20 A designates the main running-in rail at the point end of the switch; B, the main-track running-off rail at the heel end of the switch; C, the branch-track rail; D, the guard-rail, and E the movable tongue, pivoted at e. The rails C and D are bent outwardly at the points c and d, respectively, to receive between them a hard-metal filler or chock F, which extends from the point f to the point f' and forms the bed and pocket for the point 35 end of the tongue E.

The inner portion of the head of the rail D is cut away at d' to receive a raised portion f² of the said chock F, whereby the entrance to the point is guarded by harder metal than the metal of the rail. Said chock has a second raised portion f³, which takes the place of the laterally-displaced and partially-removed head of the rail C, said portion f³ at the point of the switch being equal at least 40 to full rail-head width, but gradually becoming narrower back toward the point f, at which point wheel-treads have substantially a full bearing on the tongue E. The greatest wear in a tongue-switch of this character is 45 on those portions where the wheels pass onto and off from the point of the tongue, and these I have protected by the provision of the hard-metal chock F. The bed for the

heel portion of the tongue is formed by a separate chock H of the usual character.

The rail C is given a second bend at c', bringing it outside of and alongside of the rail A, its head being slightly planed off, as shown at d', Fig. 3, to form a bearing or lifting rail for wide-tread wheels.

The several parts of the structure are secured together by means of through-bolts J, and exact fitting together of the parts is dispensed with by a filling K, of spelter or like material. L is a small chock between the rails A and C.

The construction described avoids the expense of a hard-metal bed for the tongue throughout its length. This is quite an item, as **T**-rail tongue-switches are usually of long 7c radius, and therefore of considerable length, requiring a long chock which is expensive to make and fit if wholly of hard metal. It is also unnecessary to form the guard-line of the guard-rail and the tread of the branch-track 75 rail of hard metal the full length of the switch, since back of the portions which are formed by the above-described chock there is comparatively little more wear on these parts than upon an ordinary piece of track. 80 The said chock therefore provides for the life of the switch at a minimum cost. A further advantage of the construction is that any worn or defective member of the frog may be readily replaced.

I do not wish to limit myself to the precise details of construction which I have herein shown and described, as these may be varied without departing from my invention.

Having thus described my invention, what I claim as new, and desire to secure by Letters Patent, is—

1. In a tongue-switch, the combination with the guard-rail and the branch-track rail, each bent laterally outward toward the point end of the switch, of the hard-metal filler or chock secured between the said rails and having a raised portion which takes the place of the head of the branch-track rail for a portion of its length.

2. In a tongue-switch, the combination with the guard-rail and the branch-track rail, each bent laterally outward toward the point end of the switch, of the hard-metal filler or chock secured between the said rails and having a raised portion which replaces a

part of the head of the guard-rail at the approach to the switch-tongue.

3. In a tongue-switch, the combination with the branch-track rail and the guard-rail each bent laterally outward toward the point end of the switch, of the hard-metal filler or chock secured between the said rails and forming the bed for the point portion of the tongue, said chock having a raised portion which replaces the head of the branch-track rail for a portion of its length, and a second raised portion which replaces a portion of the head of the guard-rail for a portion of its length.
- 15 4. In a tongue-switch, the combination with the main connecting-rails A and B, and the guard-rail D, of the branch-track rail C

having one end portion extended alongside the said rail B to form a bearing-rail at the point end of the switch.

5. In a tongue-switch of the character described, the combination with the guard-rail and the branch-track rail, of the two chocks F and H secured between the said rails and forming the bed for the tongue, the said chock F, having portions which form portions of the track-surface adjacent to the point portion of the tongue.

In testimony whereof I have affixed my signature in presence of two witnesses.

ISRAEL K. DIXON.
